WALL MOUNTED GARMENT RACK

Charles G. Blackwell, Trinity, Ala.

Application August 29, 1957, Serial No. 47,552

Term of patent 7 years

(Cl. D33—8)

Fig. 1 is a perspective view of a wall mounted garment rack, showing my design; and,

Fig. 2 is an end elevational view thereof.

I claim:

The ornamental design for a wall mounted garment rack, as shown.
